UNITED STATES PATENT OFFICE

LEO F. HEERWAGEN, OF FAYETTEVILLE, ARKANSAS

GEAR SHIFT LEVER PICTURE KNOB

Application filed June 16, 1930. Serial No. 461,496.

The object of my present invention is the provision of a peculiar and advantageous picture carrying knob for use on the gear shift levers of automobiles.

5 To the attainment of the foregoing, the invention consists in the improvement as hereinafter described and definitely claimed.

In the accompanying drawings, forming part of this specification:—

10 Figure 1 represents a top plan view of the invention.

Fig. 2 represents a top plan view of the invention employing a slightly different shape of knob.

15 Fig. 3 is a side elevational view of a knob shown in Fig. 1.

Fig. 4 represents a vertical sectional view through the knob shown in Fig. 1, taken substantially on the line 4—4 of Fig. 1.

20 Fig. 5 represents a vertical sectional view through a slightly modified form of knob.

Figure 6 comprises disconnected views of the parts comprised in the embodiment illustrated in Figures 1 to 4, inclusive.

25 Referring to the drawings wherein like numerals designate like parts, it will be seen that numeral 5 represents the usual threaded upper end of the gear shift lever of an automobile. Numeral 6 represents the knob body

30 provided with a circumferentially extending grip flange 7.

The upper end of the knob 6 is also provided with an outwardly disposed flange 8 which has an inwardly curved rim 9 thereon.

35 Numeral 10 represents the lens for disposition upon the picture 11 while numeral 12 represents the spring split ring which can be snapped to a position within the confines of the rim 9 to prevent displacement of the

40 lens 10.

Fig. 5 discloses a slightly modified form of knob wherein numeral 6' represents the knob body provided with the circumferential flange 7'. The upper portion of the body 6' is externally threaded for disposition within the internally threaded sleeve 8'. The upper end of this sleeve 8' is provided with an inwardly disposed transversely tapered rim 9' for engaging the lens 10' and retaining the same against the picture 11'.

Fig. 1 represents the knob of circular outline, whereas Fig. 2 represents the same in a polygonal outline.

It will be understood from the foregoing that each embodiment of my invention includes a knob characterized by spaced circumferential flanges, and also characterized by the utilization of the outermost flange to surround and frame and thereby embellish a picture retained in the knob, the picture being interposed between the knob body and a rim on the outermost flange, and being arranged at the inner side of a protective lens which is also interposed between the said rim and the body. Manifestly the two spaced flanges of the knob enable an operator to readily take secure hold of the knob.

While the foregoing specification sets forth the invention in detail, it is to be understood that numerous changes in the shape, size, and materials may be resorted to without departing from the spirit and scope of the invention as claimed hereinafter.

Having thus described my invention, what I claim as new is:—

A knob adapted for attachment to a gear shift lever and characterized by spaced circumferentially arranged flanges, one flange adjacent to the outer end of the knob and having an inwardly extending rim spaced from the knob portion within the rim, a picture arranged against said knob portion, a lens arranged at the outer side of the picture, both picture and lens disposed between said rim and the knob portion within the rim, and a split spring ring within said rim holding the picture and lens in place.

In testimony whereof I affix my signature.

LEO F. HEERWAGEN.
